UNITED STATES PATENT OFFICE.

SAMUEL H. ELLIOTT, OF ROANOKE, VIRGINIA.

AIR-BRAKE MECHANISM.

1,247,053.

Specification of Letters Patent. Patented Aug. 27, 1918.

Application filed October 6, 1917. Serial No. 195,059.

To all whom it may concern:

Be it known that I, SAMUEL H. ELLIOTT, a citizen of the United States, residing at Roanoke, in the county of Roanoke and 5 State of Virginia, have invented certain new and useful Improvements in Air-Brake Mechanisms, of which the following is a specification.

The present invention relates to automatic 10 air brakes for railway cars and the object thereof is to provide improved means for venting or exhausting the brake cylinder when it is desired to release the brakes. With such object in view the invention consists of the formation, combination and arrangement of parts as will be herein described and claimed.

In the drawings, Figure 1 is a front elevational view of the apparatus of my invention, Fig. 2 a vertical section of the same taken substantially on the line 2—2 of Fig. 3, and Fig. 3 is a side elevational view of the same. In Fig. 1 the device is shown with the front removed for clearness.

25 None of the elements making up the automatic air brake equipment are shown in the drawings as these are well known and need no detailed description. It will be briefly stated, however, that my improvements are 30 intended for use with that class of air brakes where the train pipe carries the supply of compressed air from the compressor, ordinarily located upon the locomotive. Each 35 car carries an auxiliary reservoir, a triple valve, a brake cylinder, and usually a pressure retaining valve. The train line feeds air through the triple valve to the auxiliary reservoir. Upon a reduction of pressure in the train line the triple valve shifts to close 40 off communication between the train line and the auxiliary reservoir and at the same time connects the auxiliary reservoir with the brake cylinder, thereby applying the brake. When the pressure is again raised 45 in the train line the triple shifts back to allow recharging of the auxiliary reservoir and also opens a vent from the brake cylinder to the atmosphere, through the retaining valve if such be used.

50 It is a fact of common knowledge that triples frequently stick and fail to exhaust the brake cylinder and release the brake as desired, resulting in troublesome dragging of brakes. It is to correct this feature that 55 the present invention is directed.

Referring now to the drawings, the pres-

ent embodiment of my device includes a case 4 having therein a Bourdon pressure-indicating tube 5, the pipe connection 6 being employed to connect the same with the 60 regular train line so that the tube 5 will be actuated by train line pressure. This tube 5, through the links 6, 7 and 8, and the gear lever 9 actuates gear pinion 10, the gear lever 9 being pivoted at 11 to a convenient part of the mechanism. The gear pinion 10 is secured to a shaft 12 which carries also an arm or valve lever 13.

Secured within the case 4 by means of the 65 screws 29 is the body 14 of my control valve, the shaft 12 extending within the compartment 15 of this body and the lever 13 being also located within this compartment. The compartment 15 is piped at 16 to the atmosphere or to the retaining valve as may 70 be desired. The body 14 contains a second compartment 17, the wall of metal 18 separating the two compartments and the latter being piped at 19 to the brake cylinder. The channel or port 20 passes through the 75 dividing wall 18 and connects the two compartments.

Within the compartment 15 the upper surface of the wall 18 is formed as a seat for the 80 sliding valve member 21, this latter having 85 a groove or port 22 extending in the direction of its travel and arranged to at all times overlie and communicate with the upper end of the port 20. A hole 23 extends from this groove through the valve member and is 90 fitted at its upper extremity with a small pin valve 24. The pin valve has a limited movement within the valve member 21 for opening the hole 23 to allow communication 95 between the two compartments but when the pin 25 in the valve stem engages the outer end of the slot 26 in the valve member 21, any further movement of the pin valve will 100 carry with it the entire valve member 21. Likewise after seating any further movement in that direction will carry the entire member with it. The spring 27 is provided to hold the valve member 21 to its seat. The link 28 connects the outer end of the stem of the pin valve with the lever 13.

105 The operation of my device when coupled up to the air brake parts as heretofore described is as follows:

As long as normal pressure remains in the train line the pin valve will be unseated, 110 it standing with the pin 25 at the outer end of the slot 26. When a reduction in train

line pressure is made to apply the brake the contraction of the Bourdon tube will cause the pin valve to move to the right to seat the valve and prevent communication between the two compartments and consequently between the brake cylinder and the atmosphere. When the train line pressure is again built up the expansion of the tube will cause the pin valve to shift to the left, unseating the pin valve and venting the brake cylinder, the air leaking off around the stem of the pin valve.

The elongated channel 22 allows my apparatus to be used with any desired train line pressure without altering or adjusting the device in any manner. In this way a car so equipped may be coupled in to any train and it automatically shifts to a position corresponding to the pressure carried.

I have thus described an embodiment of my invention. Other embodiments are possible within the scope of the appended claims without departing from the spirit thereof.

What I claim is:

1. In an automatic fluid pressure brake system, means in addition to the triple valve for controlling the exhaust of air from the brake cylinder comprising an additional connection from the brake cylinder to the atmosphere having a valve therein, said valve having a body with two compartments, and a dividing wall, the first of said compartments being in constant communication with the brake cylinder and the second in communication with the atmosphere, a port in the dividing wall adapted to connect the two compartments, a movable member mounted upon the dividing wall and having an elongated port communicating with the port in the divid-

ing wall at various positions of its travel, a valve within the movable member adapted to establish or prevent communication between the port thereof and one of the said compartments and means actuated respectively by increases or decreases of pressure in the train line for opening or closing the valve.

2. In an automatic fluid pressure brake system, means in addition to the triple valve for controlling the exhaust of air from the brake cylinder comprising an additional connection from the brake cylinder to the atmosphere having a valve therein, said valve having a body with two compartments, and a dividing wall, the first of said compartments being in constant communication with the brake cylinder and the second in communication with the atmosphere, a port in the dividing wall adapted to connect the two compartments, a movable member mounted upon the dividing wall and having an elongated port communicating with the port in the dividing wall at various positions of its travel, a valve within the movable member adapted to establish or prevent communication between the port thereof and one of the said compartments, means actuated respectively by increases or decreases of pressure in the train line for opening or closing the valve, the attachment of the valve to the movable member being so arranged that a slight variation of pressure in the train line will open or close the valve and that further changes in pressure will shift the movable member upon the dividing wall.

In testimony whereof I affix my signature.

SAMUEL H. ELLIOTT.
